UNITED STATES PATENT OFFICE.

WILLIAM E. BRADLEY, OF NEW YORK, N. Y.

SNOW-PLOW AND SCRAPER.

SPECIFICATION forming part of Letters Patent No. 592,192, dated October 19, 1897.

Application filed November 16, 1896. Serial No. 612,224. (No model.)

To all whom it may concern:

Be it known that I, WILLIAM E. BRADLEY, a citizen of the United States, residing at New York, in the county of New York and State 5 of New York, have invented certain new and useful Improvements in Snow-Plows and Scrapers, of which the following is a full and complete specification, such as will enable those skilled in the art to which it appertains 10 to make and use the same.

This invention relates to snow-plows, scrapers, and similar devices; and the object thereof is to provide an improved device of this class which is simple in construction and operation, 15 and which is designed for use as a road-scaper, and also as a snow-plow and for similar purposes.

The invention is fully disclosed in the following specification, of which the accompanying 20 drawings form a part, in which—

Figure 1 is a front view of my improved snow-plow and scraper, and Fig. 2 a section on the line 2 2 of Fig. 1.

In the drawings forming part of this specification the separate parts of my improvement are designated by the same numerals of reference throughout the several views; and in the practice thereof I provide a rigid frame, which consists of two side boards or 25 plates 5, which are connected by two cross plates or bars 6, which are secured to the tops thereof, adjacent to each end, and each of the side boards or plates are beveled at their lower corners, as shown at 7, and provided with metal shoes 8.

Secured to the front ends of each of the side boards or plates, which are so formed as to constitute runners, are two strong metal strips 9, which project upwardly and forwardly 40 and are provided with ordinary clevises 10, by means of which a horse or horses may be hitched thereto, and supported above said side bars or plates is a seat 11, which may be of any desired form and construction, said seat being supported by longitudinal yokes or braces 12, which are connected with the cross bars or plates 6, and by side braces 13, which are connected with the side bars or plates 5. Each of the side bars or plates 5

is also provided with a strong metal strip 14, 50 one of which is shown in dotted lines in Fig. 2, and pivoted centrally of the side bars or plates 5 is the plow or scraper proper, which consists of a board 15, to the lower edge of which is bolted a steel plate 16, the lower 55 edge of which is beveled or sharpened, as shown at 17 in Fig. 2, and said steel plate 16 is provided with arms 18, which extend transversely of the board 15, and are bolted thereto. The board 15 is also provided at each end 60 with longitudinal metal blocks 19, which are bolted thereto, and on which are formed the pivot-pins by which it is connected with the side plates or boards 5, as shown in dotted lines at 20 in Fig. 1, and secured to the plate 65 or board 15 are arms or handles 21, which extend upwardly and backwardly, and by means of which the edge of the plow or scraper proper may be held in contact with the ground or with surfaces on which the device is operated. 70

The operation will be readily understood from the foregoing description when taken in connection with the accompanying drawings and the following statement thereof. 75

The forward cross plate or bar 6 serves as a support for the feet of the driver, and in practice two men are necessary in order to operate the device, one of whom acts as a driver and the other works behind the plow 80 or scraper, and by means of the handles 21 holds the edge of the plow or scraper proper in contact with the ground or other surfaces over which the device is drawn.

My improvement is simple in construction 85 and operation, and is well adapted to accomplish the result for which it is intended, and it is evident that changes in and modifications of the construction herein described may be made without departing from the 90 spirit of my invention or sacrificing its advantages.

Having fully described my invention, I claim as new and desire to secure by Letters Patent— 95

The herein-described snow-plow, comprising a frame consisting of side boards 5, cross-plates 6, metal shoes 8, metal strips 9, cle- 95

ises 10, a seat 11, and braces 12 and 13, metal strips 14, a plow consisting of a board 15, a steel plate 16 having sharpened edges 17 and arms 18, metal blocks 19, pivot-pins 20, handles 21, all combined substantially as shown and described and for the purpose set forth.

In testimony that I claim the foregoing as

my invention I have signed my name, in presence of the subscribing witnesses, this 13th day of November, 1896.

WILLIAM E. BRADLEY.
